DESIGN FOR A PURVEYING STAND

Clio Coil, Oklahoma City, Okla.

Application December 3, 1940, Serial No. 97,033

Term of patent 3½ years

To all whom it may concern:

Be it known that I, Clio Coil, a citizen of the United States, residing in the city of Oklahoma City, in the county of Oklahoma, in the State of Oklahoma, have invented a new, original, and ornamental Design for a Purveying Stand, of which the following is a specification, reference being made to the accompanying drawings, forming a part thereof.

In the drawings:

Fig. 1 is a front elevational view of a purveying stand showing my new design.

Fig. 2 is an end elevational view thereof.

Fig. 3 is a rear perspective view on an enlarged scale.

The opposite ends of the design are identical.
I claim:

The ornamental design for a purveying stand, as shown and described.

CLIO COIL.
